UNITED STATES PATENT OFFICE.

FRANK P. D'ARCY, OF KALAMAZOO, MICHIGAN.

DESIGN FOR A SPOON.

SPECIFICATION forming part of Design No. 35,829, dated April 1, 1902.

Application filed January 27, 1902. Serial No. 91,532. Term of patent 14 years.

To all whom it may concern:

Be it known that I, FRANK P. D'ARCY, a citizen of the United States, residing at the city of Kalamazoo, in the county of Kalamazoo and State of Michigan, have invented and produced a certain new and useful Design for Spoons, of which the following is a specification.

This invention relates to a design for a spoon, fork, or like article.

The design is fully illustrated in the accompanying drawings, forming a part of the specification, in which—

Figure 1 is a plan view of a spoon embodying the features of my design. Fig. 2 is a side elevation view of the structure appearing in Fig. 1.

As shown in the drawings, the leading or material features of my design consist of the

bowl portion formed with diamond-shaped facets and a handle portion the edges of which are beaded, while toward the outer end of the handle portion is a stereotyped representation of a coat of arms the plume-like crest of which forms the tip of the handle. 25

Having thus described my invention, what I claim as new, and desire to secure by Letters Patent, is—

The design for a spoon or like articles, as herein shown and described. 30

In witness whereof I have hereunto set my hand and seal in the presence of two witnesses,

FRANK P. D'ARCY. [L. S.]
